CLAIM

The ornamental design for a display device with a moveable assembly, as shown and described.

DESCRIPTION

- FIG. 1 Shows a front perspective view of a display device with a moveable assembly attached to a flat panel display and to a base, the moveable assembly shown in a first position.
- FIG. 2 Shows a back perspective view of a display device with a moveable assembly attached to a flat panel display and to a base, the moveable assembly shown in a first position.
- FIG. 3 Shows a front view of a display device with a moveable assembly attached to a flat panel display and to a base, the moveable assembly shown in a first position.
- FIG. 4 Shows a side right view of a display device with a moveable assembly attached to a flat panel display and to a base, the moveable assembly shown in a first position.
- FIG. 5 Shows a back view of a display device with a moveable assembly attached to a flat panel display and to a base, the moveable assembly shown in a first position.
- FIG. 6 Shows a side left view of a display device with a moveable assembly attached to a flat panel display and to a base, the moveable assembly shown in a first position.
- FIG. 7 Shows a top view of a display device with a moveable assembly attached to a flat panel display and to a base, the moveable assembly shown in a second position.
- FIG. 8 Shows a bottom view of a display device with a moveable assembly attached to a flat panel display and to a base, the moveable assembly shown in a second position.
- FIG. 9 Shows a front perspective view of a display device with a moveable assembly attached to a flat panel display and to a base, the moveable assembly shown in a second position.
- FIG. 10 Shows a back perspective view of a display device with a moveable assembly attached to a flat panel display and to a base, the moveable assembly shown in a second position.
- FIG. 11 Shows a front perspective view of a second embodiment of a display device with a moveable assembly attached to a flat panel display and to a base, the moveable assembly shown in a second position.
- FIG. 12 Shows a back perspective view of a display device with a moveable assembly attached to a flat panel display and to a base, the moveable assembly shown in a second position.
- FIG. 13 Shows a front view of a display device with a moveable assembly attached to a flat panel display and to a base, the moveable assembly shown in a second position.
- FIG. 14 Shows a side right view of a display device with a moveable assembly attached to a flat panel display and to a base, the moveable assembly shown in a second position.
- FIG. 15 Shows a back view of a display device with a moveable assembly attached to a flat panel display and to a base, the moveable assembly shown in a second position.
- FIG. 16 Shows a side left view of a display device with a moveable assembly attached to a flat panel display and to a base, the moveable assembly shown in a second position.
- FIG. 17 Shows a bottom view of a display device with a moveable assembly attached to a flat panel display and to a base, the moveable assembly shown in a first position; and,
- FIG. 18 Shows a top view of a display device with a moveable assembly attached to a flat panel display and to a base, the moveable assembly shown in a first position.
